UNITED STATES PATENT OFFICE.

JOHN L. HARVEY, OF MILWAUKEE, WISCONSIN, ASSIGNOR TO CHAIN BELT COMPANY, OF MILWAUKEE, WISCONSIN, A CORPORATION OF WISCONSIN.

ELECTRIC HEATING APPARATUS.

Application filed May 31, 1927. Serial No. 195,435.

This invention relates to electric heaters and has for one of its objects to provide an electric heating apparatus which is particularly adapted for the heating of rods, preparatory to subjecting them to die action, whereby they are headed to form the connecting pins of conveyer chains and the like.

A further object of the invention is to provide an electric heater of the class described having readily adjustable means whereby the length of the portion of the rod which is to be heated may be readily controlled.

A still further object of the invention is to provide an induction heater of the class described having readily removable water-cooled jaws or electrodes and having means whereby wear of said electrodes may be readily and quickly compensated.

A still further object of the invention is to provide a heater of the class described which will be simple in construction, comparatively inexpensive to manufacture and install and more efficient in use than those which have been heretofore proposed.

With the above and other objects in view which will appear as the description proceeds, the invention consists in the novel details of construction, and combinations of parts more fully hereinafter described, and particularly pointed out in the appended claims.

Referring to the accompanying drawings forming a part of this specification in which like reference characters designate like parts in all the views:

Figure 1 is a side elevational view of a heater constructed in accordance with the present invention;

Fig. 2 is a top plan view of the jaws or electrodes and their associated parts;

Fig. 3 is a longitudinal vertical sectional view taken approximately on the plane indicated by the line 3—3 of Fig. 2; and,

Fig. 4 is a wiring diagram illustrating the electrical circuits.

In the said drawings, the numeral 10 indicates generally a supporting frame work which includes uprights 11 and upper horizontal members 12, 13 and 14. Rigidly secured to the member 14 as by bolts 15 is a bracket 16 which supports the stationary jaw indicated generally by the numeral 17. This jaw structure comprises a cooling chamber 18 secured to the bracket 16 by bolts 19 through which chamber, cooling water or

other fluid is adapted to be passed by means of pipes 20 and 21.

Inasmuch as the jaw structure carries the heating current, a sheet of insulating material 22 is preferably interposed between the cooling chamber 18 and the bracket 16 to insulate the frame from the jaw.

Detachably secured to the cooling chamber 18 by bolts 23 is the copper electrode 24 which is provided with a substantially semi-cylindrical recess or groove 25.

Coacting with the stationary electrode 17 is a movable electrode structure indicated generally by the numeral 26, the construction of which will now be described.

Rigidly secured to the horizontal member 12, as by the bolts 27 is a hollow cylindrical bearing block or member 28 provided at one end with a removable head 29 into which is threaded an adjustable plug 30, as will be clear from Figs. 2 and 3. A plunger 31, is 75 slidably mounted in the bearing block 28 and is prevented from rotating therein by means of a key 32. Said plunger is hollowed out as at 33 to receive a coil spring 34, one end of which seats against the bottom 35 of the bore 33 while the other ends seats against the threaded plug 30, above described. The plunger 31 has detachably secured to it, as by the bolts 36, a hollow cooling chamber 37 similar to the chamber 18, a sheet of insulating material 38 being interposed between the plunger 31 and the cooling chamber 37, as will be readily understood. Cooling water is conducted to and from the cooling chamber 37 through the pipes 39 and 40 and the said cooling chamber has detachably secured to it as by the bolts 41, a copper jaw 42 which is a duplicate of the jaw 24 and which is provided with the substantially semi-cylindrical recess or groove 43.

The plunger 31 has threaded into it as at 45, one end of an axial rod 46 which rod passes through a bore 47 provided in the threaded plug 30 and terminates at the bifurcated connecting member 48 through which it is connected to a lever 49 pivoted as at 50 in a bracket 51 carried by the frame work 10. A pin and slot connection 52 provides the necessary lost motion to compensate between the arcuate movement of the lever 49 and the straight line movement of the rod 46, as will be readily understood. The said rod 46 is threaded as at 59 and carries a pair of lock

nuts 58 which serve as stops to limit the forward travel of the movable electrode, as will appear more fully below.

The lever 49 has pivotally secured to it, as at 53, a rod or link 54 which is provided with a turn buckle 55 by means of which the length of the said link 54 may be adjusted. The link 54 is pivotally connected as at 56 to a foot lever 57 by means of which the movable electrode is moved in one direction as will appear more fully below.

As above stated, the copper jaws 24 and 42 are duplicates whereby they are interchangeable and their semi-cylindrical recesses or grooves 25 and 43 are aligned to form a substantially cylindrical pin receiving recess. In order to control the length of the portion of the pin or rod which is to be heated, there is provided within this recess, a set screw 60 which is threaded into the horizontal member 18, and which is adjustable up and down, as will be readily understood, to act as a stop to control the length of the portion of the pin received between the jaws 24 and 42. In other words, by lowering the screw 60, a longer portion of the pin is receivable between the jaws, while by raising the screw 60, a shorter portion of the pin will be received between the jaws and heated. As shown in Fig. 3 the stop screw 60 is smaller in diameter than the recess formed by the two semi-cylindrical grooves 25 and 43 of the jaws 24 and 42 respectively, so that when a rivet or pin is gripped between the said jaws the latter do not contact with the stop screw which consequently is not included in the heating circuit.

The stationary and movable electrodes 17 and 26 are provided with suitable brackets 61 and 62 respectively, which carry the secondary coils of the electrical transformer 63 which is mounted within the frame 10. The ends of the secondary winding 65, as will be clear from the wiring diagram shown in Figure 4, are connected respectively to the jaws 24 and 42 while the primary winding 66 of the said transformer is tapped at a plurality of points throughout its length, the said taps 67 leading to contacts 68 which are adapted to be engaged by a suitable switch handle 69 whereby the effective length of the primary may be controlled and in this manner the induced current in the secondary may likewise be controlled. In actual use upon a two hundred and twenty volt single phase, sixty cycle circuit, the amperage in the primary may range from forty to seventy-five while that in the secondary may be made to range from four thousand to ten thousand at from one to three volts.

The operation of the heater will be clear from the foregoing but it may be briefly summarized as follows:

With the parts in the positions as illustrated in Figs. 1, 2 and 3, in order to insert a pin or rod between the jaws 24 and 42, it is

only necessary to depress the foot lever 57 which, through the link 54 and rocking lever 49 will exert a pull on the rod 46 and through it upon the plunger 31. This pull will move the electrode 26 toward the left as viewed in Figs. 2 and 3 against the pressure of the spring 34, thereby separating the jaws 42 and 24 sufficiently to permit the rod or pin to be inserted between them. The distance to which the said rod or pin is inserted will be governed by the position of the stop screw 60 and upon the release of the foot lever 57, the movable electrode will be returned toward the right as viewed in said figures by the spring 34, whereby the jaws 42 and 24 will be caused to grip the rod. Current now being passed through the primary of the transformer, the induced current set up in the secondary thereof, will pass through the portion of the pin between the jaws 42 and 24, thereby heating such portion, as will be readily understood. When the desired temperature has been reached, the foot lever 57 is again depressed to release the pin which is withdrawn and placed in suitable dies to form the head thereon.

If desired, an automatic switch 70 may be employed which is actuated by the foot lever 57 so that when the latter is released the primary circuit will be automatically closed to immediately start the heating and when the lever is depressed the circuit will be broken to cut off the current and stop the heating.

The pressure exerted by the spring 34 to move the electrode 26 toward the right, as viewed in the drawings, may be controlled by adjusting the threaded plug 30, as will be readily understood. Likewise, if the jaws 24 and 42 become worn, such wear may be compensated for through adjustment of the turn buckle 65 and the stop nuts 58 upon the threaded portion 59 of the rod 46.

While one form of the invention has been thus illustrated and described, it is obvious that those skilled in the art may vary the details of construction as well as the precise arrangements of parts without departing from the spirit of the invention and therefore, it is not wished to be limited to the above disclosure except as may be required by the claims.

What is claimed is:

1. In an electric heater of the class described, a pair of electrodes having recesses adapted to receive the work to be heated; and an adjustable stop member for determining the proportion of said work received between said electrodes, said stop member being positioned between said electrodes within said recesses and being of smaller dimensions than said recesses, whereby it will remain out of contact with said electrodes.

2. An electrode structure for electric heaters comprising a support; and a cooling chamber provided with a work-engaging jaw secured to and insulated from said support,

said cooling chamber and jaw being adapted to be included in the heating circuit of the heater.

3. An electrode structure for electric heaters, comprising a support; a cooling chamber detachably secured to and insulated from said support; and a readily detachable jaw carried by said chamber.

4. In an electric heater of the class described, a frame; a stationary electrode mounted on said frame; a bearing block mounted on said frame in spaced relation to said electrode; a plunger slidably mounted in said block; a movable electrode carried by said plunger; a spring normally urging said plunger and movable electrode toward said stationary electrode; and means for moving said plunger and movable electrode away from said stationary electrode.

5. In an electric heater of the class described, a frame, a stationary electrode mounted on said frame; a bearing block mounted on said frame in spaced relation to said stationary electrode; a plunger slidably mounted in said block; a movable electrode carried by said plunger; a plug threaded in said bearing block; a spring interposed between said plug and said plunger, normally urging said plunger and movable electrode toward said stationary electrode; and means for moving said plunger and movable electrode away from said stationary electrode.

6. In an electric heater of the class described, a frame; a stationary electrode mounted on said frame; a bearing block 35 mounted on said frame in spaced relation to said stationary electrode; a plunger slidably mounted in said block; a movable electrode carried by said plunger; a spring normally urging said plunger and movable electrode to 40 toward said stationary electrode; a rod connected to said plunger; means carried by said rod for limiting the movement of said movable electrode toward said stationary electrode; and means connected to said rod for 45 moving said plunger and movable electrode away from said stationary electrode.

7. In an electric heater of the class described, a frame; a stationary electrode mounted on said frame; a bearing block 50 mounted on said frame in spaced relation to said stationary electrode; a plunger slidably mounted in said block; a movable electrode carried by said plunger; a spring normally 55 urging said plunger and movable electrode toward said stationary electrode; a rod connected to said plunger; means carried by said rod for limiting the movement of said movable electrode toward said stationary electrode; and means connected to said rod including a foot lever and an adjustable link 60 for moving said plunger and movable electrode away from said stationary electrode.

JOHN L. HARVEY.
